FLUSHING DEVICE FOR WATER CLOSETS

William Scott, Medford, Mass.

Application June 15, 1937, Serial No. 148,294

5 Claims. (Cl. 137—104)

This invention relates generally to flushing devices for water closets, and more particularly to a flushing device which has no discharge valve.

It is a common experience that present-day flushing devices frequently fail to completely stop the discharge of water after the flushing of a closet with the result that larger or smaller quantities of water continuously splash into the closet bowl. Not only is the continuously discharging or leaking water from the flushing device wasted, but it causes a monotonous splashing noise which may become very annoying. Leakage of a flushing device is most frequently caused by an imperfectly seating discharge valve in the bottom of the water tank of the flushing device. The usual attempt by laymen to reseat the valve properly is mostly futile in that leakage therethrough usually recurs after a few flushings of the closet bowl, and the valve is in the end usually replaced at a cost.

It is the primary aim and object of the present invention to provide an improved flushing device which dispenses with any valve through which water must pass on its way from the supply tank to the closet bowl.

It is also among the objects of the present invention to provide a flushing device which, on a single manipulation even before the tank is entirely refilled with water after a previous flushing of the closet bowl, automatically flushes the latter as soon as the tank is refilled with water.

It is another object of the present invention to provide a flushing device which is of simple and durable construction and which can be produced at a comparatively small cost.

These and other objects of the present invention, together with means whereby the latter may be carried into effect, will best be understood from the following description of an illustrative embodiment thereof shown in the accompanying drawings. The particular device described and shown has, however, been chosen for purposes of exemplification only, as it will be obvious to those skilled in the art that the invention, as defined by the claims hereunto appended, may be otherwise embodied without departure from the spirit and scope thereof.

In said drawings:

Fig. 1 is a cross sectional view of a flushing device, embodying the present invention.

Fig. 2 is a plan view of said flushing device.

Fig. 3 is an enlarged, fragmentary section, taken substantially on the line 3—3 of Figs. 1 and 2.

Fig. 4 is a section through certain controlling

mechanism of the flushing device, the section being taken substantially on the line 4—4 of Fig. 3.

Figs. 5 and 6 are sections similar to that shown in Fig. 4, showing certain elements of said control mechanism in different positions of operation, however.

Fig. 7 is an exploded plan view of certain connected elements of said control mechanism.

Fig. 8 is a front elevation of the elements of Fig. 7 in their assembled relation.

Fig. 9 is a perspective view of another element of said control mechanism.

Referring to the drawings and more particularly to Fig. 1, the reference numeral 10 designates the usual water tank which may be made of any suitable material, such as porcelain. Extending through the bottom 11 of said tank is a threaded pipe union 12 which is secured to said bottom by a nut 13. Pressed between the tank bottom 11 and an annular flange 15 of the union 12 is a packing 17 of any suitable material. Screwed or otherwise secured to the union 12 is the long limb 19 of a syphon 20, the short limb 21 of which extends into close proximity to the tank bottom 11. The limbs 19 and 21 are joined at the top in any suitable manner by a return bend 22 which may be of any suitable construction. For reasons which will appear obvious later, it is preferable to construct the syphon in such manner that the continuous passage through the return bend 22 and the limbs 19, 21 is of substantially uniform cross-sectional area throughout. It can be noticed in Fig. 1 that the water in the tank is normally at the level 24 substantially at the summit 25 of the syphon 20.

A pipe 18 is also secured in any suitable manner to the union 12 and is adapted to conduct water from the tank 10 to the closet bowl (not shown). Extending through the tank bottom 11 is another threaded pipe union 26 which is secured thereto by a nut 27. Pressed between the tank bottom 11 and an annular flange 29 of the union 26 is a packing 28. Screwed or otherwise secured to the union 26 is a pipe 30 which carries at its upper end a control mechanism 31, commonly called a "ballcock". Also secured to the union 26 is another pipe 30a which is in permanent communication with any suitable source of water under pressure, such as tap water. The control mechanism 31 comprises a valve casing 32 (see Fig. 4) which is suitably secured to a hollow member 33, threaded at 34 to the upper end of the pipe 30. The valve casing 32 is provided with a central chamber 35 which is closed at the bottom by the

15

55

member 33, and two opposite chambers 36 and 37 which are in communication with said central chamber at 38 and 39, respectively. It can be observed in Fig. 4 that the opposite chambers 36, 37 are situated on different levels for reasons which will appear obvious later. Suitably secured to the valve casing 32 and communicating with chamber 36 thereof is a pipe 40 which extends into closer proximity to the tank bottom 11 than the short limb 21 of the syphon 20. Also suitably secured to the valve casing 32, but communicating with the chamber 37 thereof, is another pipe 41 which is U-shaped and has its free limb 41a projecting into the short limb 21 of the 15 syphon 20. Axially slidable in the central or distributing chamber 35 of the valve casing 32 is a cup-shaped member 42, having a central hub 43 and ports 44 and 45 in opposite sides of the cylindrical wall of said member 42. These ports 20 44 and 45 are located on different levels and adapted to communicate at opportune times with the entrances 38 and 39 to the chambers 36 and 37, respectively, and thus establish communication between the central valve chamber 35 and 25 the adjacent valve chambers 36 and 37 respectively. Secured to the bottom of the member 42 by means of a screw 47 is the valve proper 46 which is preferably a leather disc. The member 33 provides a seat 48 for said valve 46. Resting 30 against the hub 43 of member 42 is a short stud 49 which is axially slidable in a neck portion 50 of the valve casing 32, and provided with a laterally projecting finger or lug 51 which is guided for movement longitudinally of said stud in a 35 slot 52 in said neck portion 50. The neck portion 50 is provided with integral, spaced arms 53 on which is mounted a stub shaft 54, rotatably supporting two elements 55 and 56. The arms 53 straddle said elements 55, 56 to prevent axial 40 movement of the latter on their supporting shaft 54. Element 55 is in the form of a lever, having one arm 57 in engagement with the top surface 58 of the stud 49, and having its other arm 59 provided with a laterally projecting lug 60 which 45 engages the adjacent arm 53 of the valve casing and serves as a stop for further rotation of the element 55 in clockwise direction beyond the position shown in Fig. 5. The other element 56 has a depending cam lug 61 which is in alignment 50 with the earlier mentioned finger 51 of the stud 49. A rod 62, carrying at one end a conventional float or ball 63, is adjustably connected with the element 56 in the following manner. As best 55 shown in Fig. 7, element 56 is provided with a hub 64, having a frusto-conical surface 65 against which a frusto-conical surface 66 of the rod 62 is clamped by means of a thumb screw 67, extending through the hub 68 of rod 62 and being threaded into the hub 64 of element 56. Upon 60 loosening the screw 67, the float-carrying rod 62 may be angularly adjusted relative to the element 56, and said rod 62 is again secured to the element 56 in any angularly adjusted position relative thereto by merely tightening said screw 65. Element 56 is provided with an integral arm 56a which is so manipulated during angular adjustment of the float-carrying rod 62 that the valve 46 cannot leave its seat 48 and admit water into the tank 10. The element 56 is further provided with spaced arms 69 (Figs. 3, 7 and 8) which support a pin 70 on which a lever 71 is rotatably mounted. Lever 71 is engaged on opposite sides by the arms 69 and thus prevented from axial movement on its supporting pin 70. Mounted on 70 the front wall of the tank 10 in a manner to be

described hereafter is a bracket 72 which pivotally supports at 73 a bell crank lever 74, having one arm connected with the free end of the lever 71 by a link 75 in the manner best shown in Fig. 3. Extending through an opening 76 in the front wall of the tank 10 is the threaded, hollow shank 77 of a knob 78 which is secured to said front wall by nuts 79, received by said shank 77 and firmly drawn against the base 80 of the earlier mentioned bracket 72, thus also securing the latter to said front wall. Located in an annular recess 81 of the knob 78 is a pre-loaded compression spring 82 which bears against a push button 83, having a long shank 84, extending through the hollow shank 77 of the knob 78 and threadedly receiving on its forward end a nut 8 which is normally forced into engagement with said shank 77 by the spring 82 as shown in Fig. 3. The forward end of the shank 84 is in alignment with the other arm 85 of the earlier mentioned lever 74, and it can now be understood that on manipulating the button 83 inwardly against the compression of the spring 82, the lever 74 will be rocked counterclockwise and the lever 71 will be rocked clockwise (all as viewed in Fig. 3) through 25 intermediation of the link 75 which connects both levers 71 and 74. In the normal position of the lever 71 as shown in Fig. 3, i. e., when the push button 83 is not manipulated, a part of said lever 71 near its pivotal support 70 is in operative 30 alignment with a shoulder 86 of the element 55, and said lever 71 is raised out of operative alignment with said shoulder 86 and into the position shown in Fig. 5 on manipulation of the push-button 83. The pressure of the water in the supply pipe 30 (Fig. 4) tends to raise the valve 46 from its seat 48 and, consequently, to shift the valve carrying member 42 into the position shown in Fig. 5. However, this water pressure is insufficient to actually raise the valve 46 from its seat 40 45 inasmuch as the float 63, due to its favorable leverage, exerts a greater valve-closing force against the stud 49 through intermediation of the element 55 and lever 71 which normally locks said element to the float-carrying rod 62. On manipulating the push-button 83, the lever 71 is rocked out of locking engagement with the shoulder 86 of the lever element 55 so that the latter is suddenly free to rotate from the position shown in Fig. 4 into the position shown in Fig. 5, 50 and the water pressure in the supply pipe 30 will then quickly raise the valve 46 from its seat 48 and shift the valve-carrying member 42 and the thereon resting stud 49 into the position shown in Fig. 5 in which the port 45 of said element 42 is in full communication with the valve chamber 37, while the other port 44 of said element 42 is out of communication with the other valve chamber 36. Thus, upon manipulating the push button 83, the valve 46 is quickly opened 60 and water under pressure passes into the valve chamber 37 and through the U-shaped pipe 41 into the short limb 21 of the syphon 20 (Fig. 1). When the suddenly released water under pressure discharges into the short limb 21 of the 65 syphon 20, the latter is primed and immediately starts to siphon most of the water in the tank therefrom. Obviously, the air in the return bend 22 and in the longer limb 19 of the syphon must first be removed therefrom before said syphon 70 can perform its siphonic action. This is quickly accomplished by the stream of water under pressure from the U-shaped pipe 41 which passes into and through the short limb 21, and through the return bend 22 of the syphon 20, and escapes 75

through the long limb 19 of said siphon. This stream of water immediately starts a flow of the water column in the short limb 21 of the siphon into and through the return bend 22 thereof and out through the longer limb 19. The mass of water first rushing through the return bend 22 and through the longer limb 19, though not at first filling said return bend and said longer limb, displaces part of the air therein and carries the remaining air with it due to the high velocity of said water mass which operates on the injector principle. While a comparatively high pressure of the tap water is essential for a quick start of the siphonic action of the present flushing device, it has been found from experience that the water pressures in most communities, though varying to a considerable extent, are sufficient to start siphonic action of the flushing device promptly upon manipulation of the push-button 83. Once the siphon becomes operative, most of the water in the tank is quickly discharged therefrom and the water level in the tank drops accordingly fast and carries with it the float 63. While the float 63 thus follows the rapidly dropping water level in the tank, the lever 71 rides for a short distance on the peripheral portion 90 of the lever element 55 and finally drops by gravity upon the diametrically smaller peripheral portion 91 of said element 55 and into operative realignment with the shoulder 86 thereof. Immediately after the float 63 begins to drop with the water level in the tank on a siphonic discharge of water therefrom, the cam lug 61 of the rod 62 engages a cam surface 92 of the earlier mentioned finger 51 of the stud 49 and starts to depress said stud and the valve carrying member 42 against the pressure of the tap water to which the valve 46 is permanently subjected. This gradual depression of the valve-carrying member 42 results in a gradual throttling of the passage between the port 45 of said element 42 and the valve chamber 37 and, consequently, in a gradually diminishing flow of water through the U-shaped pipe 41 and into the short limb 21 of the siphon 20. At the end of a siphonic discharge of water from the tank this passage has been throttled to the approximate extent illustrated in Fig. 6, and the valve 46 has approached its seat 48 to a corresponding extent. Also, while the passage between the port 45 of the valve-carrying member 42 and the valve chamber 37 is thus gradually throttled, the other port 44 of said member 42 moves gradually into communication with the other valve chamber 36 and admits water from the supply pipe 30 to the auxiliary filler tube 40. Thus, near and at the end of a siphonic discharge of water from the tank 10, less water from the supply pipe 30 is admitted to said tank, and the admitted water is furthermore partly diverted through the auxiliary filler tube 40. By this provision, the water level in the short limb 21 of the siphon 20 is little disturbed near and at the end of a siphonic discharge. The water level in the tank near the end of a siphonic discharge falls below a plurality of perforations or vents 100 in the short limb 21 of the siphon (Fig. 1), whereupon air enters said short limb 21 through said vents and gradually breaks the continuous water column in the siphon without giving rise to the rattling noise which usually occurs at the end of a siphonic discharge through a siphon which is suddenly, rather than gradually, vented. To further insure gradual venting of the siphon, the open end of the short limb 21 is made sloping as shown

in Fig. 1. After the siphon ceases to draw water from the tank, the water level in said tank immediately starts to rise again, carrying with it the float 63. Inasmuch as the lever 71 is then in operative alignment with the shoulder 86 of the lever element 55 (Fig. 6), the latter soon follows the float-carrying rod 62 in its counterclockwise rotation as viewed in Fig. 6 when said lever 71 engages said shoulder 86 and commences to depress the stud 49 and the valve-carrying member 42. Engagement between the lever 71 and the shoulder 86 takes place substantially when the cam lug 61 of the rod 62 permits the valve-carrying member 42 to assume its entirely open position, and when the tank 10 is approximately half refilled with water. In the entirely open position of the valve 46 only the port 45 of the valve-carrying member 42 is in full communication with the valve chamber 37, while the other port 44 of said member 42 is intercepted from communication with the other valve chamber 36. Thus, immediately after a concluded siphonic discharge of water from the tank, water from the supply pipe 30 is admitted in limited quantities to both pipes 40 and 41 through the partly depressed valve-carrying member 42, and said member 42 is permitted gradually to move substantially into the fully open position shown in Fig. 5 and admit gradually increasing quantities of water to the pipe 41 and gradually decreasing quantities of water to the pipe 40, when the water level in the tank starts to rise again. When the member 42 arrives substantially in its fully open position, the lever element 55 resumes control over said member 42 and commences to depress the same again. During such depression of the member 42, the passage between its port 45 and the valve chamber 37 is gradually throttled and constantly decreasing quantities of water are admitted to the U-shaped pipe 41 until the valve 46 finally comes to rest on its seat 48. However, irrespective of the gradual throttling of the passage between the port 45 and the valve chamber 37, a substantially uniform quantity of water per time unit is discharged into the tank until the water level therein nearly reaches its normal level 24. This is due to the fact that the other port 44 of the valve-carrying member 42 moves gradually into full communication with the valve chamber 36 as the passage between the port 45 and the valve chamber 37 is gradually throttled. When the rising level in the tank nearly reaches its normal level 24, the passage between the port 44 of the member 42 and the valve chamber 36 is gradually throttled until the valve 46 comes to rest against its seat 48. Thus, while the water under pressure from the supply pipe 30 is delivered, due to the gradually throttled passage between the port 45 and the valve chamber 37, in gradually decreasing quantities into the short limb 21 of the siphon substantially during the latter half of the refilling of the tank with water, the port 44 in the valve-carrying member 42 provides sufficient communication between the central or distributing valve chamber 35 and the auxiliary filler pipe 40 to divert water into the latter in sufficient quantities to substantially compensate for the continuous decrease in the quantity of water delivered to the pipe 41 until the water level in the tank nearly reaches its normal level 24. From then on less and less water per time unit is admitted to the tank until the valve 46 finally comes to rest against its seat 48 and the water level in the tank reaches its normal maximum level 24.

The present flushing device is of simple and durable construction which can be manufactured at a small cost. The assembly of the flushing device is very simple and requires hardly any skill 5 because the siphon parts 19, 21 and 22 may be assembled as a separate unit, and the entire control mechanism 31 may be assembled in a separate unit, whereupon said pre-assembled units may be readily installed in the tank. Those 10 parts of the flushing device which are submerged in water are preferably made of corrosion-resistant material. Thus, the valve casing may be a bronze casting and most other parts of the control mechanism 31 may be made of corrosion-resistant steel. Also, it is advisable to provide a slight clearance between the relatively sliding surfaces of the elements of said control mechanism as the ordinary tap water in most communities contains traces of alkalis which will deposit 15 in the control mechanism. These deposits would in time interfere with the movement of certain elements of said mechanism if the relatively sliding surfaces of the control mechanism would have practically no clearance.

20 While the present flushing device has the advantage that it is entirely valveless between the tank and the closet bowl and, therefore, has eliminated any possibility for the leakage of water into the closet bowl as frequently caused 25 by such a valve, it is also possible to refill the closet bowl by manipulating the push-button 83 before the tank is refilled after a previous flushing of the closet. More particularly, the flushing device will be conditioned for an automatic 30 refilling of the closet when the push-button 83 is manipulated after the lever 71 has engaged the shoulder 86 of the lever element 55 during the refilling of the tank. However, the refilling of the closet will not take place until 35 the tank is refilled. Obviously, when thus manipulating the push-button 83, the lever 71 is immediately withdrawn from locking engagement with the shoulder 86 of the lever element 55, and the valve 46 will then be forced by the pressure 40 of the water from the supply pipe 30 into the entirely open position shown in Fig. 5, with the result that the water in the tank rises quickly to its normal level 24 and the continuing water stream into the short limb 21 of the siphon starts 45 a new siphonic action.

50 It is also fully within the purview of the present invention to dispense with the auxiliary filler pipe 40, the valve chamber 36 and the port 44 in the valve-carrying member 42 so that all the 55 water for refilling the tank is discharged into the short limb 21 of the siphon. The gradually closing valve 46 and the gradually throttled passage between the port 45 of the valve-carrying member 42 and the valve chamber 37 admit such 60 small quantities of water into the short limb 21

of said siphon when the water level in the tank approaches and finally reaches its normal level 24, as to preclude a self-starting siphonic discharge of the water from the tank.

I claim:

1. In a flush tank apparatus, the combination of a valve adapted to be normally urged open by water under pressure from a source; a fixed pivot; two elements independently rotatable on said pivot, one element engaging the valve and the other element carrying a float; a member locking said elements in close proximity to their pivot for combined rotation in valve-closing direction only during the ascent of said float; and means including a push button for releasing said member from interlocking engagement with said elements. 10

2. The combination in a flush tank apparatus as set forth in claim 1, in which one of said elements has a radial shoulder and said member 20 is pivotally mounted on the other element at right angles to the pivot axis of the elements and engages said shoulder for combined rotation of said elements in valve-closing direction.

3. In a flush tank apparatus, the combination 25 of a valve normally urged open by water under pressure from a source; two pivotally mounted elements, one engaging the valve and the other carrying a float and having a portion partially closing the valve and permitting reopening of 30 the same during the latter part of the descent and the corresponding early part of the ascent, respectively, of said float; a member interlocking said elements for combined rotation in valve-closing direction only during another part of 35 the ascent of said float; and means for releasing said member from interlocking engagement with said elements.

4. The combination in a flush tank apparatus as set forth in claim 3, in which the valve comprises a casing having a lateral water outlet and a longitudinal slot, and a cup-shaped valve member 40 slidable in said casing and having a lateral port in axial alignment with said outlet and a laterally projecting finger extending through said 45 slot and being engaged by said portion of said other element.

5. The combination in a flush tank apparatus as set forth in claim 3, in which the valve comprises a casing having a lateral water outlet and 50 a longitudinal slot, and a cup-shaped valve member slidable in said casing the bottom of which cooperates with a vent to control the flow of water, said valve member having a lateral port 55 in axial alignment with said outlet and a laterally projecting finger extending through said slot and being engaged by said portion of said other element.

WILLIAM SCOTT. 60
